UNITED STATES PATENT OFFICE.

ALFRED J. LOVELESS, OF LENOX, MASSACHUSETTS.

REVERSIBLE TAG.

1,242,007.

Specification of Letters Patent.

Patented Oct. 2, 1917.

Application filed April 5, 1917. Serial No. 159,991.

To all whom it may concern:

Be it known that I, ALFRED J. LOVELESS, a citizen of the United States, and a resident of Lenox, in the county of Berkshire 5 and State of Massachusetts, have invented a new and Improved Reversible Tag, of which the following is a full, clear, and exact description.

My invention has for its object to provide 10 a tag having a body which may be stamped out of sheet metal and be quickly bent into shape, the body having a guideway in which a card may be slipped to exhibit either side as desired.

15 Additional objects of the invention will appear in the following specification, in which the preferred form of the invention is disclosed.

In the drawings similar reference characters denote similar parts in all the views, 20 in which—

Figure 1 is a plan view showing my reversible tag;

Fig. 2 is a sectional view on the line 2—2 25 of Fig. 1;

Fig. 3 is a sectional view on the line 3—3 of Fig. 1; and

Fig. 4 is a plan view showing the body 30 after it has been stamped, but before it has been bent into shape.

By referring to the drawings, it will be seen that the body member is stamped out of a single piece of metal, as illustrated in Fig. 4, this body 5 having two arms 6 and 7, 35 the arm 6 being disposed at the end 8 of the body and having an orifice 9 which registers with an orifice 10 in the body when the body at the line 11 is bent over so that the terminals 12 of the arms 6 and 7 are disposed adjacent the side 13 of the body. This side 13 40 of the body is bent over after the body 5 has been bent at the line 11, so that the side 13 beyond the line 14 will be disposed over the terminals 12 of the arms 6 and 7. The bent-over sides at the lines 11 and 14 of the body 5 form guideways for a card 15 on the sides of which addresses or other information may be printed or written. A cord is disposed through the orifices 9 and 10 when the 45 body has been completed, these orifices registering with each other, as has been stated. The cord disposed through the orifices 9 and 10 and tied, serves to hold the arm 6 in place, and as this arm 6 is integral with

the side 16 of the body 5 beyond the line 11, 55 it assists in holding this side 16 in bent position. The outer end of the card 15 is reinforced by a metal piece 17 which is bent over to clamp the end of the card, this metal piece fitting snugly the ends of the guideways 60 formed by the bent-over sides 13 and 16 of the body 5 to prevent the card 15 from slipping out of the body.

Having thus described my invention, I claim as new, and desire to secure by Letters Patent:

1. In a reversible tag, a body in one piece having a plurality of arms extending from a side of the body, one of the arms being disposed adjacent an end of the body, the body adjacent the arms being bent over with the terminals of the arms disposed adjacent the opposite edge of the body, which is bent over against the terminals of the arms, there being registering orifices in the said end 75 of the body and in the arm disposed at the said end of the body, through which a cord may be disposed.

2. In a reversible tag, a body in one piece having a plurality of arms extending from a side of the body, one of the arms being disposed adjacent an end of the body, the body adjacent the arms being bent over with the terminals of the arms disposed adjacent the opposite edge of the body, which is bent over against the terminals of the arms, the bent-over portion of the body forming guideways, there being registering orifices in the said end of the body and in the arm disposed at the said end of the body, through 90 which a cord may be disposed, and a card removably disposed in the guideways formed by the bent over sides of the body.

3. In a reversible tag, a body having a plurality of arms extending from a side of the body, one of the arms being disposed adjacent an end of the body, the body adjacent the arms being bent over with the terminals of the arms disposed adjacent the opposite edge of the body, which is bent over against the terminals of the arms, there being registering orifices in the said end of the body and in the arm disposed at the said end of the body, through 100 which a cord may be disposed.

4. In a reversible tag, a body in one piece having two arms extending from a side of the body one of the arms being disposed ad-

5 jacent an end of the body, the other arm being spaced from the other end of the body, the body adjacent the arms being bent over with the terminals of the arms disposed adjacent the opposite edge of the body which is bent over against the terminals of the arms, there being registering orifices in the first mentioned end of the body and the ad-

10 jacent arm, a cord disposed through the registering orifices, and a card removably disposed in the guideway formed by the bent-over sides of the body, the card being removable from the second mentioned end of the body.

ALFRED J. LOVELESS.
